US0D1015876S

(12) **United States Design Patent** (10) **Patent No.:** **US D1,015,876 S**
(45) **Date of Patent:** **** Feb. 27, 2024**

(54) **CAN LID**

(71) Applicant: **Silgan Containers LLC**, Woodland Hills, CA (US)

(72) Inventors: **David Dunn**, Palmyra, WI (US); **Elizabeth A. Metzger**, Wauwatosa, WI (US); **John Schindewolf**, Rochelle, IL (US); **Alvin Widitora**, Los Angeles, CA (US); **Dave Wood**, Oconomowoc, WI (US); **Seth Moore**, Oconomowoc, WI (US); **Andrew Palumbo**, Conshohocken, PA (US)

(73) Assignee: **Silgan Containers LLC**, Woodland Hills, CA (US)

(**) Term: **15 Years**

(21) Appl. No.: **29/875,367**

(22) Filed: **May 3, 2023**

Related U.S. Application Data

(62) Division of application No. 29/819,670, filed on Dec. 16, 2021, now Pat. No. Des. 988,864, which is a division of application No. 29/761,485, filed on Dec. 9, 2020, now Pat. No. Des. 939,956, which is a division of application No. 29/712,555, filed on Nov. 8, 2019, now Pat. No. Des. 907,489, which is a division of application No. 29/626,050, filed on Nov. 14, 2017, now Pat. No. Des. 879,609.

CLAIM

We claim the ornamental design for a can lid, as shown and described.

DESCRIPTION

FIG. 1 is a top view of the claimed design; and,

FIG. 2 is a top perspective view of FIG. 1.

The ornamental design which is claimed is shown in solid lines in the drawings.

1 Claim, 2 Drawing Sheets
